15 Claims. (Cl. 179—90)

The invention relates to a pulsing device for telephone installations, which device is accommodated in one housing.

The purpose of the invention is to ensure reliable 15 actuation of and very safe operation of such a pulsing device of low production cost.

A pulsing device for telephone installations is known which is operated by interchangeable cams which are longitudinally non-displaceable and can be rotated mechanically by means of a power drive. The control combinations in any given case are set on the cams.

Associated with the cams are a common locking pawl and individual movable follower member each serving to follow one cam. Before each selection process the 25 followers are moved manually from their rest position to their operating position. The followers remain in the operating position for the duration of the selection process, automatically connect the power drive for the cams, and disconnect the apparatus again, returning the elements which were moved to their initial state, when a person has been selected by transmitting the desired 30 number-combination by operation of a key. In the operating state the followers are in range both of the corresponding cam and of the locking pawl. On the cam there are the impulse-combinations representing a desired 35 telephone number. In its operating position, the follower which has been moved by pressing the associated key is then located between the cam and the locking pawl so that the telephone number, represented by raised and recessed portions on the cam, moves the locking pawl. In the known construction a short-circuiting contact was then operated in synchronism with this movement of the locking pawl.

The short-circuiting contact operated transmitted the 40 impulses to the telephone network. The movement of the contact had to be a true image of the combination of raised and recessed portions on the cam, for the desired telephone number, made up of current impulses, to be transmitted undistorted. Wrong connections could be 45 made, for example if the current was cut off while the cams were operating, or if some members were made inaccurately and thereby contacts were not opened or closed at the correct time. It was also difficult to exchange the cams, and this could also cause wrong connections.

The invention aims to avoid these disadvantages and to 50 construct the pulsing device so that it can be manufactured with comparatively little precision, for example by stamping the individual members, and yet has a high degree of accuracy in transmitting series of impulses, is very reliable in operation and makes wrong connections extremely improbable if not impossible.

According to the invention, the moved locking pawl, 55 acting through a clutch, drives an impulse and a locking wheel and thus operates the impulsing send and interval contacts.

In this construction, a short-circuiting contact is no 60 longer operated directly or indirectly through levers, but through the medium of a clutch. The clutch, which has

2

an impulse and a locking wheel, ensures that series of impulses are transmitted accurately, even if the locking pawl does not move very accurately due to lack of precision in manufacture.

5 It is desirable for the clutch to be a slipping clutch which is driven by the drive for the cam and is locked by an impulse pawl which engages in the locking wheel and which simultaneously closes the send contact when the locking pawl causes the locking wheel to be released.

It is sufficient for the locking pawl to actuate a clutch. The clutch then ensures that, by operating the appropriate send and interval contacts, an impulse is followed by the correct interval by an interruption of the loop. Thus the pawl is now used only to release the clutch and no longer has the function of transmitting both the send impulse and the interval in the correct relative rhythm.

20 It is desirable for the clutch to be released by means of angle levers which are connected to the locking pawl through levers. The clutch itself is constructed with the locking and the impulse wheel mounted against relative rotation on a hollow bush with a friction surface, the hollow bush being mounted on the driving shaft and resiliently urged against the friction surface which is fixed to the latter.

25 The locking and the impulse wheel operate the send and the interval contact respectively. An impulse pawl drops into the locking wheel which is simultaneously operating the send contact, so that at an exactly defined point of time when the locking pawl makes the impulse pawl move, the send and interval contacts are successively closed at the correct timing sequence, the sequence of send impulses and intervals is now as accurate as if 30 interruption were effected directly from a dial. As stated above, the movement of the locking pawl no longer needs to initiate exactly the interval of time between the impulses and the interruptions, since it is only responsible for starting and stopping the clutch after each impulse. Any errors which may arise due to inaccuracy in manufacture thus make themselves felt only during a short 35 partial movement of the clutch, and when the next movement is made release is once more accurate. With the known construction, all the errors made while a cam is running are summated. Such a cam, which—according to the numbers selected—sometimes had to transmit 40 80 to 100 different impulses, had to be manufactured with great precision, and also all the movements from the start through the cam to the stopping process and the transference of movement to the locking pawl and short-circuiting contact had to be made with so little play that any practical applications of such a pulsing device was impossible, since production costs were much too high, or else in the course of time wrong connections were inevitable due to inevitable inaccuracy, slackness, the action of heat, etc.

45 The driving shaft for the clutch is preferably connected to the drive for the cams by a worm drive.

50 The impulse wheel and the locking wheel are preferably each provided with three recesses offset by 120°, which alternately open the interval contact when the send contact is closed and vice versa.

55 It is also important for the recesses in the locking wheel to have rising surfaces for operating the send contact and sharply stepped surfaces to prevent the locking wheel from rotating after the impulse pawl has dropped in.

60 Owing to the construction of the impulse and the locking wheel, the starting position defined, which is arrived at following appropriate operation by the locking pawl after the impulse pawl has dropped, enables the locking wheel, so to speak, to run always from zero without allowing any errors to be summated, as stated above. Since 65 there are three cams offset by 120°, the path correspond-

ing to the 120° is available to compensate for any errors. It is a simple matter to use suitable reductions or possibly more or less cams in order to gain still more time to compensate for errors occurring when the movement is transferred from the raised and recessed portions of the cam until the clutch is released.

Operating safety is increased if a stop lever, which is moved in known manner by the follower and allows the cam to rotate, has a pawl at the end facing the follower, which pawl positively engages the follower and is in the region of the switch for the drive, the switch being attached to one end of an angle lever of which the other end is acted upon by a switching cam connected to the control cams.

This construction makes use of a switch with a movable operating lug. The effect of this is that whenever it is at all possible to operate the switch the apparatus is ready for use. If the operating lug is outside range of the pawl, the switch cannot be operated. By simply adjusting this conveniently designed micro- or snap-switch great operating safety can be obtained with simple means.

In order to cut out the noise made by the followers following the cams but not in the operating position, a lifting disc can be provided coaxially with the control and switching cams, the lifting disc having a cam which is followed by the roller of a lever and which, through a lifting pawl, raises those followers which are not involved in the selection process out of range of the locking pawl and cams.

In order to prevent the apparatus from continuing to operate if the current is suddenly cut off, it is desirable for the switch for the drive also to operate a magnet of which the armature carries a stop pawl which, when the armature is attracted, engages in known manner behind a neb of the follower when the latter is in the operating position.

In this construction the followers are thus arrested electromagnetically, so that any current failure or any changes in the circuit necessarily return the apparatus to the rest position and simultaneously disconnect it, so that normal telephone operation cannot be disturbed.

The keys moving the followers preferably have U-shaped recesses which engage projections from the followers.

This construction prevents excess lost motion, since the positive connection given by the keys moves the followers more surely.

Another essential for reliable operation is that the cams can easily be exchanged even by a layman without the operating efficiency of the apparatus suffering. The cams are changed if the keys are to select different telephone numbers. There are various possible methods of doing this.

It is desirable, however, for the cams to have a main radial slot with a groove in one side, the groove being arcuate and serving to receive a rotary locking shaft having a flat.

In known constructions resilient elements were inserted, which required a certain dexterity to operate and move and were also quite expensive to produce. The cams are placed on the shaft by means of flattened portions provided on the latter to cooperate with the main slot.

In this way the cams are fixed against rotation on the shaft which causes the cams to be driven and rotated.

The locking shaft has a slot which acts as a keyhole for a key turning the shaft.

The rotation of the locking shaft towards the free or closed position is limited by a spring roller mounted on one side of the shaft with an abutting segment, so that secure fastening of the cam is ensured in all cases.

The keyhole is preferably covered by a plate pivoted by gravity, so that the key and stopping pin can be inserted only when the apparatus is in a specific position.

The purpose of such a construction is to make it impossible to remove cams when they cannot drop out by

their own gravity. It is also impossible to start up the apparatus when the key is still inserted, since an appropriate stopping pin prevents this.

A further operating safeguard consists in providing a send and a relay contact actuated by the handset cradle in the circuit of the magnet and the motor switch respectively to allow the cams to be driven only when the handset has been raised.

It is impossible to operate the apparatus if the handset is not raised. In the known construction, one could operate it beforehand and had to accept the fact that impulses were transmitted which did not become effective in the telephone network. Incorrect number selection was thus inevitable.

Examples of the invention are illustrated in the accompanying drawing which, together with the related description, contains further features of the invention. In the drawings:

FIG. 1 is a diagrammatic view of a cam with the support member in the rest position and with the clutch through which the impulses are transmitted;

FIG. 2 is a diagrammatic front elevation of the clutch with the corresponding working and rest contacts for transmitting series of impulses;

FIG. 3 is a side elevation of a section along the line F-F in FIG. 2;

FIG. 4 is a section along the line G-G in FIG. 2;

FIG. 5 is a diagrammatic view of the control roller with the locking shaft at the side from which the latter is turned;

FIG. 6 is a side elevation of FIG. 5 along the line A-A;

FIG. 7 is a section along the line B-B in FIG. 5;

FIG. 8 is a section along the line C-C in FIG. 5;

FIG. 9 is a section along the line D-D in FIG. 5;

FIG. 10 is a section along the line E-E in FIG. 5, and

FIG. 11 shows a stamped cam with raised and lowered portions for transmitting series of impulses.

The housing and the keys mounted therein are constructed as described in German Patent No. 1,034,218.

FIG. 1 shows the control shaft 1, which carries with it a cam 2 in the direction of the arrow 3 without relative rotation. The cam, as shown in FIG. 11, has raised portions 4 and recesses 5 which determine the impulse-sequence of the impulses and of the numbers dialled. The cam 2 is monitored by a cam follower member 6 when the latter is in the operating condition. In the position shown, movement of the follower in the direction of the arrow 7 would bring the projection 8 of the follower into a groove 9 in a locking pawl 10 but would not move the locking pawl. Thus the neb 11 of the follower, which neb is reciprocated by successive contact with the raised portions 4 and recesses 5, does not produce any movement of the locking pawl. According to how many keys are provided and how many selectable numbers the apparatus contains, the cams 2 and followers 6, together with the corresponding number of keys, are arranged one behind the other perpendicularly to the plane of FIG. 1 at a spacing such as is shown, for example, in FIG. 5.

A lifting cam disc 12 and switching disc 13, to be described below, are however associated with all the followers in common. When the key 14 is depressed in the direction of the arrow 15, then its U-shaped recess 16 entrains the projection 17 on the follower 6 and thus moves the latter in the direction of the arrow 18. The follower is, in known manner, guided for linear motion by a guide groove 19, in which a guide member 20 is mounted. At the side facing the cam, the follower has a neb 21, a recess 22 and a neb 23. A spring 24 endeavours to draw the follower 6 in the opposite direction to the arrow 18. When it moves in the direction of the arrow 18, however, the recess 22, which is positively engaged by a pawl 25, pivots the latter about its fulcrum 26 in the direction of the arrow 27, so that it operates the actuating pin 28 of the motor and magnet switch 29. This

70
75

switch connects the drive (not shown) for the shaft 1 and also the magnet 30, the armature 31 of which pivots the stop pawl 32 about its fulcrum 33 so that it comes to rest behind the neb 23. The follower 6 is thus arrested in its operating position. Unlocking is effected electromagnetically, i.e. when the current has been cut off, both the spring 44 for the magnet and the motor-magnet switch immediately bring these elements out of the range of action of their actuating members and enable the follower 6 to spring back into the rest position.

As soon as the shaft 1 and cam 2 have completed a revolution in the direction of the arrow 3, the neb of the disc 13 (shown at the top of FIG. 1) pivots a large angle lever, to the other end of which the motor and magnet switch 29 is fixed. This brings the switch out of the range of the switching pawl 25. The switch 29 therefore opens and cuts off the energisation of the electromagnet 30. The follower 6 is now freed and moves opposite to the direction of the arrow 18. At the same time a spring 47 pivots the check lever 46, since the pawl 25 turns anti-clockwise. This brings the projection 48 into contact with the recess 49 in the disc 13. The system which is movable as a unit is thus arrested again in the correct starting position for the next switching step.

When the pawl 25 switches on the switch 29 by means of the check lever 46, it simultaneously causes the latter to pivot its projection 48 out of the recess 49 in the disc 13 under the force of the spring 47. This ensures that the disc 13 and thus the roller 1 cannot move until the drive for the shaft has been switched on. It is desirable also to mount a slipping clutch between the shaft and the drive, in order to make the cam 2 immediately start turning at a uniform speed, thus ensuring that the impulses are transmitted accurately and any fluctuations in the starting conditions of the drive cannot affect the accuracy of the arrangement.

When the shaft 1 moves in the direction of the arrow 3, the lifting cam disc 12 also rotates and, when an associated follower roller 50 has moved up to the surface 51 on the disc 12, the lifting pawl 52 then pivots about its fulcrum 53, thus bringing all the followers 6 to rest on the pawl 52, together with their cams, out of range of the raised portions 4 of the cam 2. However, if the follower 6 has been moved in the direction of the arrow 18, its recess 21 drops behind the lifting pawl 52, so that the neb 11 simultaneously passes into range of the raised and recessed portions of the cam 2 and its projection 8 moves under the projection 54 of the locking pawl 10. The neb 11 and projections 8 and 54, which are now reciprocating in the direction of the arrow 7, make the locking pawl 10 pivot about its axis of rotation 55 in synchronism with these movements. The reciprocating movement is transferred by a lever 56, pivoting about its fulcrum 57, to the angle lever 58, pivoting about its fulcrum 59, thus also moving the angle lever 60, which bears on the lever 58 and pivots about its fulcrum 61. It will be appreciated that the movement of the locking pawl 10 can be enlarged by an appropriate choice of these levers or of other known types of lever systems. The angle lever 60 then moves the impulse pawl 62, which is in the form of a lever, about its fulcrum 63 against the tension of the spring 64. As shown in FIGS. 2 and 3, one end of the impulse pawl 62 bears on a sharply stepped surface 66 of the locking wheel 67. If the impulse pawl or the end 65 is moved in the direction of the arrow 68 (FIG. 3), then the clutch 69 (shown in its entirety in FIG. 2) can operate, since it is constantly driven through a worm drive 70 by the drive for the shaft 1. Under the action of the spring 73, the driving shaft 71 urges a friction disc 72, which is fixed to the shaft 71, towards a friction disc (not shown) fixed on the hollow bush 74. The locking wheel 67 and impulse wheel 75 are mounted on the hollow bush against relative rotation. When the end 65 of the impulse pawl 62 moves in the direction of the arrow 68, both the locking wheel 67 and the impulse

wheel 75 rotate in the same direction as the driving shaft 71.

Both the locking wheel and the impulse wheel have recesses which are offset by 120°. In the locking wheel rising surfaces 77 adjoin sharply stepped surfaces 66, forming lugs, while the impulse wheel has projections 78 which are stepped on both sides.

Movement of the impulse pawl 62 in the direction of the arrow 68 simultaneously closes a contact 79, which is inserted in the line to the exchange, as known in telephone technique. This contact, which is now acting as a working contact and forming the impulsing loop, is then interrupted by a contact 80 also in the exchange line acting as an interval contact. Alternate operation of the contacts produce the desired series of impulses.

Manufacturing inaccuracy is compensated for, in that it is important only, for example, for the work contact to be closed at some time while the interval contacts are opened an interposed projection 78, thus causing a circuit-break. The work contact must then become active at a range offset by 120° after the interval contact has closed. This considerably simplifies production, since the locking pawl 10 is used only to release the clutch 69 and any inaccuracy in the transference of impulses is compensated for by the enforced neutral position when the impulse pawl 62 locks the locking wheel 67.

Possible constructions to make it easy to change the cams are shown in FIGS. 5 to 11. These consist in providing the shaft 1 with flattened portions 81, 82 (FIG. 10) so that a guide member 83 is adapted for insertion in a main slot 84 of the cam 2. The main slot has an arcuate groove 85 which is engaged by a locking shaft 86 when it is turned into the position shown in FIG. 8. If the locking shaft 86 is turned by the key 87 far enough in the direction of the arrow 88 (FIG. 8) for the straight surface 89 to be aligned with the main slot 84, then the cam 2 can be drawn out in the direction of the arrow 90 without any trouble. Correct positioning of the locking shaft 86 both when it is locked, as shown in FIG. 8, and when it is released, is obtained by means of a spring roller 91, which is pressed by an annular spring 92 against an abutting extension 93 attached to the locking shaft 86. This ensures definite engagement in one or other position.

In order to ensure that the cam 2 can only be removed when the apparatus is turned upside down the projection 94 on the locking shaft 86, which is engaged by the slot 95 of the key 87, is covered by a cover plate 96. A keyhole 97 in the cover plate has a slot 98 which is adapted to cooperate with the arresting pin 99 of the key. When the key is in position the pin 99 can rotate the extension 93. Also provided on the housing is a flap 100 which pivots by gravity about its fulcrum 101. In the position shown in FIG. 6 it is impossible to insert the key 87, since the flap 100 covers the keyhole 97. If the apparatus is tilted, for example, in the direction of the arrow 102, then the flap 100 eventually exposes the keyhole, since the cover plate 96 now changes its position in relation to the flap 100.

This means that the cams 2 can be changed only in a specific operating position. If the apparatus is returned to the normal position without the key being pulled out, then the key cannot be removed, so that in any event the apparatus is ready to operate only if the members are in their structurally correct position. Only when the apparatus is mounted ready to operate does the flap 100 drop back into a position where it exposes the slot 98, and the arresting pin 99 can then be pulled out through the slot.

The invention can be applied to all cases where a pulsing device, ready to operate and functioning efficiently, is to be made with low production costs and little expenditure on adjustment.

What we claim is:

1. Pulse transmitter for telephones comprising: at

least two rotatable cams; a follower member for each of said cams, normally kept out of the range of its respective associated cam; a common locking pawl actuated by said follower members in synchronism with cam action thereupon; a key associated with each of said follower members for selectively placing such associated follower member in the actuating ranges of its associated cam and of said locking pawl; means actuated in synchronism with selection of a follower member for retaining said follower member after selection thereof in said actuating ranges of said cam and of said locking pawl; means actuated in synchronism with said cams for removing said selected follower member from said actuating ranges; a rotatable pulse wheel; a first contact actuated by said pulse wheel; a rotatable locking wheel; a second contact actuated by said locking wheel; driving means; and means operated by said locking wheel for simultaneously connecting said locking wheel and said pulse wheel to said driving means.

2. Transmitter as set forth in claim 1, said keys being angle levers having a U-shaped recess receiving a projection of its associated follower member for engagement therewith.

3. Pulse transmitter for telephones comprising: at least two rotatable cams; means for driving said cams; a follower member for each of said cams, normally kept out of the range of its respective associated cam; a common locking pawl actuated by said follower members in synchronism with cam action thereupon; a key associated and engaged with each of said follower members for selectively placing said associated follower members in the actuating ranges of its associated cam and of said locking pawl; means actuated in synchronism with selection of a follower member for retaining said follower member after selection thereof in said actuating ranges of said cam and of said locking pawl; means actuated in synchronism with said cams for removing said selected follower member from said actuating ranges; a pulse wheel and a locking wheel mounted for rotation in unison; means for disengageably, drivingly connecting said two wheels to said driving means; contact means individually actuated by said wheel; and a pawl linked to said locking pawl and engaging and disengaging said locking wheel in synchronism with actuation of said locking pawl so as to govern engagement of said wheels to said driving means.

4. Pulse transmitter for telephones comprising: at least two rotatable cams; means for driving said cams; a follower member for each of said cams, normally kept out of the range of its respective associated cam; a common locking pawl actuated by said follower members in synchronism with cam action thereupon; a key engaged with each of said follower members for selectively placing said engaged follower member into the actuating ranges of its associated cam and of said locking pawl; means actuated in synchronism with selection of said follower member for retaining said follower member after selection thereof in said actuating ranges of said cam and of said locking pawl; means actuated in synchronism with said cams for removing said selected follower member from said actuating ranges; a pulse wheel and a locking wheel mounted for rotation in unison; means for disengageably, drivingly connecting said two wheels to said driving means; contact means individually actuated by said wheels; a double arm lever having one arm selectively engaging and disengaging said locking wheel so as to govern engagement of said wheels with said driving means; and linkage means including at least one angle-lever for linking said locking pawl to the other arm of said double arm lever for actuation thereof in synchronism with actuation of said locking pawl.

5. Pulse transmitter for telephones comprising: at least two rotatable cams; means for driving said cams; a follower member for each of said cams, normally kept out of the range of its respective associated cam; a common

locking pawl actuated by said follower members in synchronism with cam action thereupon; a key engaged with each of said follower members for selectively placing said engaged follower member into the actuating ranges of its associated cam and of said locking pawl; means actuated in synchronism with selection of a follower member for retaining said follower member after selection thereof in said actuating ranges of said cam and of said locking pawl; means actuated in synchronism with said cams for removing said selected follower member from said actuating ranges; a pulse wheel and a locking wheel mounted on a hollow shaft; a second shaft receiving said hollow shaft and being geared to said driving means, there being means including spring and friction means for drivingly engaging said hollow shaft with said second shaft; contact means individually actuated by said wheels; and means linked to said locking pawl and engaging and disengaging said locking wheel in synchronism with actuation of said locking pawl so as to govern engagement of said two shafts.

6. Transmitter as set forth in claim 5, said second shaft being geared to said driving means by a worm gear.

7. Transmitter as set forth in claim 5, said wheels each are provided with recesses offset by 120°, whereby each 25 wheel opens its associated contact means when the other wheel closes its associated contact means.

8. Pulse transmitter for telephones comprising: at least two rotatable cams; means for driving said cams; a follower member for each of said cams, normally kept out of the range of its respective associated cam; a common locking pawl actuated by said follower members in synchronism with cam action thereupon; a key engaged with each of said follower members for selectively placing said engaged follower member into the actuating ranges 30 of its associated cam and of said locking pawl; means actuated in synchronism with selection of a follower member for retaining said follower member after selection thereof, in said actuating ranges of said cam and of said locking pawl; means actuated in synchronism with said cams for removing said selected follower member from said actuating ranges; a locking wheel having gradually sloping cam surfaces respectively succeeded along the circumference thereof by sharply dropping flanks; a pulse wheel connected to said locking wheel and mounted for rotation in unison therewith; means for drivingly engaging said driving means with said two wheels; contact means individually actuated by said wheels; and means linked to said locking pawl and scanning said cam surfaces and flanks of said locking wheel so as to govern engagement of said two wheels with said driving means in synchronism with actuation of said locking pawl.

9. Pulse transmitter for telephones comprising: at least two rotatable cams; means for driving said cams; a follower member for each of said cams, normally kept out of the range of its respective associated cam; a common locking pawl actuated by said follower members in synchronism with cam action thereupon; a key engaged with each of said follower members for selectively placing said engaged follower members into the actuating ranges 55 of its associated cam and of said locking pawl; means actuated in synchronism with selection of a follower member for retaining said follower member after selection thereof in said actuating ranges of said cam and of said locking pawl; a stop lever for arresting any of said cams in a preselected position and being engageable with said selected follower member for moving out of the arresting position; switch means governing said driving means and being actuated by said stop lever; means actuated in synchronism with the rotation of said cams for removing said selected follower member from said actuating ranges 60 of said cam and of said locking pawl thereby causing said stop lever to be placed into its arresting position; a rotatable pulse wheel; a first contact actuated by said pulse wheel; a rotatable locking wheel; a second contact actuated by said locking wheel; and means operated by 65 70 75

said locking pawl for simultaneously connecting said locking wheel and said pulse wheel to said driving means.

10. Pulse transmitter for telephones comprising: at least two rotatable cams; means for driving said cams; a follower member for each of said cams, normally kept out of the range of its respective associated cam; a common locking pawl actuated by said follower members in synchronism with cam action thereupon; a key engaged with each of said follower members for selectively placing said engaged follower member into the actuating ranges of its associated cam and of said locking pawl; means including a lifting disc rotating with said cams and further including a lifting pawl actuated by said disc for placing any non-selected follower member out of the ranges of its associated cam and of said locking pawl upon rotation of said cams; means actuated in synchronism with selection of a follower member for retaining said follower member after selection thereof in said actuating ranges of said cam and of said locking pawl; means actuated in synchronism with said cams for removing said selected follower member from said actuating ranges of said cam and of said locking pawl; a rotatable pulse wheel; a first contact actuated by said pulse wheel; a rotatable locking wheel; a second contact actuated by said locking wheel; and means operated by said locking pawl for simultaneously connecting said locking wheel and said pulse wheel to said driving means.

11. Pulse transmitter for telephones comprising: at least two rotatable cams; means for driving said cams; a follower member for each of said cams, normally kept out of the range of its respective associated cam; a common locking pawl actuated by said follower members in synchronism with cam action thereupon; a key engaged with each of said follower members for selectively placing said engaged follower member into the actuating ranges of its associated cam and of said locking pawl; magnet means for retaining said selected follower member in said ranges; switch means governing said driving means and said magnet means and being actuated by said selected follower member; means actuated in synchronism with said cams for removing said selected follower member from said actuating ranges of said cam and of said locking pawl; a rotatable pulse wheel; a first contact actuated by said pulse wheel; a rotatable locking wheel; a second contact actuated by said locking wheel; and means operated by said locking pawl for simultaneously connecting said locking wheel and said pulse wheel to said driving means.

a second contact actuated by said locking wheel; and means operated by said locking pawl for simultaneously connecting said locking wheel and said pulse wheel to said driving means.

12. Pulse transmitter for telephones comprising: a main shaft; means for driving said shaft; at least two cams, each having a slot for mounting on said shaft, each slot having an arcuate groove; a locking shaft extending parallel to said main shaft, projecting through said slots and locking said cams to said main shaft when projecting into said arcuated groove; a follower member for each of said cams, normally kept out of the range of its respective associated cam; a common locking pawl actuated by said follower members in synchronism with cam action thereupon; a key engaged with each of said follower members for selectively placing said engaged follower member into the actuating ranges of its associated cam and of said locking pawl; means actuated in synchronism with selection of a follower member for retaining said follower member after selection thereof in said actuating ranges of said cam and of said locking pawl; means actuated in synchronism with said cams for removing said selected follower member from said actuating ranges; a rotatable pulse wheel; a first contact actuated by said pulse wheel; a rotatable locking wheel; a second contact actuated by said locking wheel; and means operated by said locking pawl for simultaneously connecting said locking wheel and said pulse wheel to said driving means.

13. A transmitter as set forth in claim 12, in which a spring roller is provided on one end of said main shaft, which spring roller bears on an abutting segment fastened on said locking shaft in order to fix the locking shaft in position.

14. A transmitter as set forth in claim 13, in which the locking shaft ends in a slot which acts as a keyhole for a key for turning the locking shaft.

15. A transmitter as set forth in claim 14, in which the keyhole is covered by a gravity-biased plate, so that the key with its stopping pin can be inserted only when the apparatus is in a specific position.
